CLAIM

We claim the ornamental design for a cover for a probe or the like, as shown and described.

DESCRIPTION

FIG. 1 is a top perspective view of a cover for a probe or the like according to our new design;

FIG. 2 is a bottom perspective view thereof;

FIG. 3 is a cross-section view thereof taken from line 3-3 shown in FIG. 7;

FIG. 4 is an enlarged view of area 4 circumscribed in FIG. 3;

FIG. 5 is a bottom plan view thereof;

FIG. 6 is a side elevation view thereof; and,

FIG. 7 is a top plan view thereof.

The dash lines immediately adjacent to the shaded areas depict boundaries of the claim and portions of the cover for a probe or the like that form no part of the claimed design. The dash dot dash lines shown in FIGS. 3 and 4 depict boundaries of the claim and form no part of the claimed design. All other dash lines in the drawings depict portions of the cover for a probe or the like that form no part of the claimed design.
